DOUBLE APRON FESTOON DRIER

Alpheus O. Hurxthal, Philadelphia, Pa., assignor
to Proctor & Schwartz, Incorporated, Philadelphia, Pa., a corporation of Pennsylvania

Application June 15, 1933, Serial No. 676,000

11 Claims.

(Cl. 34—12)

This invention relates to driers for relatively loose materials, such as alfalfa, grass and other vegetable materials, wool, hair and other animal materials, and fibrous materials of all kinds which heretofore have been spread on a horizontally disposed conveyer movable in a horizontal plane through a closure or chamber where-in a drying medium, usually heated air, is circulated in a downward direction substantially perpendicular to and through the conveyer and the layer of material carried thereby.

In a drying apparatus of this type an extremely long drying chamber is frequently required, with the conveyer traveling continually at a moderate rate of speed consistent with the rate at which the conveyer may be properly loaded, in order to obtain maximum capacity and delivery and at the same time insure proper drying of the material being handled.

As the length of the machine increases the initial installation and maintenance costs increase proportionately as also does the amount of floor space required to accommodate the machine. As the length of the machine increases the heat losses also increase requiring an additional amount of piping or other internal radiation to compensate for such heat losses.

The object of the present invention is to reduce the length of the drying chamber without sacrificing efficiency or capacity and at the same time reduce the initial installation, maintenance and operating costs, and to eliminate such other disadvantages as are incidental to the use of the relatively long drying chamber.

The present invention primarily contemplates the elimination of the strictly horizontal conveyer in the drying chamber by the provision of suitable means projecting laterally beyond the side edges of the conveyer, whereby the conveyer may be hung in suitably spaced festoons on suitable carriers moving horizontally in and through the drying chamber, whereby the length of the drying chamber may be accordingly reduced, the floor space likewise reduced, and the amount of radiation necessary for maintaining a predetermined temperature within the drying chamber reduced to a minimum as a result of the reduction in the heat losses effected by the use of the shorter drying chamber.

In order to prevent slipping of the layer of material on the inclined portions of the festooned conveyer the present invention further contemplates the use of means projecting upwardly from the material-carrying face of the conveyer for

entrance into the layer of material thereon, whereby relative movement between the conveyer and the layer of material is eliminated or reduced to a negligible degree.

In order to obviate tumbling of the material on the conveyer along the inclined portions of the festoons the present invention contemplates the provision of a holding element disposed in superposed substantially parallel relation to the supporting conveyer and resting on the layer of material disposed intermediate the two.

For purposes of efficiency, the holding element is preferably in the form of an endless belt of a foraminous nature, as is the carrying conveyer, in order to permit free circulation of the drying medium through the superposed elements and the layer of material held therebetween.

As a result of the use of the hold-down belt, the drying medium may be circulated in both directions perpendicular to the layer of material or transversely thereof in order to keep the material in a light, fluffy condition free of packing.

The holding belt is preferably automatically laid on the material at or adjacent the feed end of the drier after the material has been spread on the carrying element and before the formation of the festoons; and removed from the material, automatically, after the material has been dried to the desired extent, preferably after the two superposed elements have been drawn out of the festoons adjacent the delivery end of the drier. However, in some instances the hold-down element may be withdrawn at any desired place in the course of travel of the conveyer and hold-down element at which the material has dried and become more or less matted or interlocked to such an extent that it has attained the form of a continuous web or sheet wherein the tendency of the material to tumble in the festoons is practically nil.

In some instances, for example when the material is of a relatively coarse nature, the anti-slip means, projecting from the carrying face of the supporting conveyer into the layer of material thereon, may be eliminated when the hold-down belt is employed; and in other instances, for example when the material is of a relatively fine nature, both the supporting conveyer and the hold-down belt may be equipped with the anti-slip means, which preferably take the form of spikes or teeth.

The construction and operation of the mechanism forming the subject of the present invention will be fully disclosed hereinafter, reference being had to the accompanying drawing, of which:

Fig. 1 is a diagrammatic longitudinal side elevation of a loose material drier made in accordance with the principles of the present invention; and

5 Fig. 2 is a view similar to Fig. 1, illustrating the anti-slip means on both the supporting conveyer and the hold-down belt.

As shown in the drawing, the drier comprises a closed casing 1 including a relatively short drying chamber 2 having heating chambers along 10 one or both sides thereof in which steam pipes or other internal heat radiating means is provided but not shown in the present drawing as such arrangement is common in driers of various types.

15 In the present instance, the drier is shown as having circulating fans 3, 3 located at the top of the drying chamber for circulating air through the heating and drying chambers, to maintain the circulating air at a predetermined temperature 20 for drying material carried through the drying chamber longitudinally thereof.

In the present instance the material to be dried is of a relative loose character, the present machine being particularly adapted for drying alfalfa as it comes from the field and before it is 25 baled for shipping.

The material is supported in and carried through the drying chamber 2 by and on one face of an endless foraminous belt or apron 5, which 30 at spaced intervals longitudinally thereof is provided with transversely extending supports or girts 6, which are secured thereto and extend laterally beyond the opposite side edges thereof respectively.

35 The supporting belt or apron 5 passes around a guide roller 7 disposed outside and spaced from one end of the casing 1 adjacent the base line of the casing; and upwardly in an inclined plane, as indicated at 8, to and over a feed roller or drum 10 disposed adjacent the top and one end of the casing 1.

The supporting apron 5 is fed into the casing 1 continuously, between two laterally spaced carrier chains or belts 11, the upper runs 12 of which are disposed in a horizontal plane and are engaged by the laterally extending ends of the girts 6, 6, whereby the apron 5 is formed into festoons A, A, which are supported by and between the girts 6, 6.

40 The spacing of the girts 6 on the carriers 11 is determined by the rate of travel of the upper runs 12 of the carriers 11 relative to the rate of feeding of the apron 5 into the casing 1, by which the spacing of the festoons A, A is governed.

45 The apron 5 is drawn out of the festoons A, A successively by a drum 15 similar to and having the same surface speed as the feed drum 10, whereby the apron 5 is removed from the casing 1 at the delivery end thereof at the same rate of speed at which it is fed into the opposite end of the casing by the feed drum 10.

The carrier chains 11 may be driven at a predetermined rate of speed relative to the feed and discharge of the apron 5, by means of sprockets 13 secured to the shaft 14 of the discharge drum 15 while the drums 10 and 15 may be synchronously driven by any suitable means, not shown.

50 The apron 5, after leaving the discharge drum 15, passes around guide rolls 8 and 9 back to the first mentioned guide roll 7 at the feed end of the casing 1, either through the bottom of the casing as shown, or in a channel provided below the base of the casing as desired.

55 The material to be dried is fed to and spread on the conveyer apron 5, in the present instance,

by a feed hopper 16 provided with an elevator apron 17 which receives the material from a conveyer 18 at the bottom of the hopper and delivers it to the top of the hopper between the rear wall 19 thereof and an inclined front wall 20, the lower edge of which is disposed slightly above the carrying face of the apron 5 to prevent the material from sliding down the incline 8 of the apron 5, while the lower edge of the rear wall 19 of the hopper is spaced above the carrying face of the apron 5 to spread the material thereon in a uniform layer of predetermined thickness.

60 The material, indicated at x, is carried upwardly by the inclined portion 8 of the apron 5 and immediately behind the rear wall 19 of the loading hopper 16 the hold-down apron 25 is laid on top of the layer of material x by a guide roll 24, from which the hold-down apron travels forward and over the feed drum 10 with the conveyer apron 5 resting on the layer of material x in superposed spaced relation to the conveyer apron 5, maintaining this relation to the conveyer apron 5 and the layer of material x as the two are fed into the casing 1 and formed 65 into festoons on the carrier chains 11, the hold-down apron 25 being formed into festoons A¹, A¹ which respectively agree with the festoons A, A of the conveyer 5.

70 At the delivery end of the casing 1 the conveyer apron 5 and the hold-down apron 25 pass around the delivery drum 15, whereupon the conveyer apron 5 with the layer of material x thereon passes downwardly to the guide roll 8, where the layer of material x is dumped into a chute 26 which may deliver the material to a baler or other suitable device for future handling, while the hold-down apron 25 passes upwardly around a guide roll 21 and a pair of guide rolls 22 and 23 to the guide roll 24 at the rear end of 75 the feed hopper 16.

The hold-down apron 25 may be driven at the same rate of speed as the feed drum 10 to keep the two in synchronization by driving any or all of the rolls 21, 22, 23 and 24, from any suitable source, not shown, but in some instances the friction of the material x against the under surface of the hold-down apron 25 is sufficient to drive the apron 25 at the same rate of speed as the conveyer apron 5.

80 As noted above one or the other or both the aprons 5 and 25 may be provided with anti-slip means to maintain the layer of material x against movement relative to the apron 5 and for this purpose Fig. 2 illustrates each of the 85 aprons 5 and 25 as being provided with upwardly extending pins or spikes 30 and 31 respectively which project into the layer of material x carried by the conveyer apron 5, thereby holding the material against any substantial movement 90 relative to the apron 5 as the latter is formed into the festoons A, A.

95 In cases where the hold-down apron is also used and is provided with the pins 31 such pins preferably alternate with the pins 30 of the 95 conveyer apron 5, and in such a case the pins 31 obtain sufficient purchase in the layer of material x as to drive the apron 25 without other mechanical power being applied to the guide rolls 7 21, etc.

100 In order to prevent slippage of the girts 6, 6 on the carrier chains 11, spaced links of said chains may be equipped with pockets to receive the projecting ends of the girts, thereby definitely 7.

spacing the girts uniformly on the carrier chains 11.

I claim:

1. The combination in a conveyer of a pair of freely separable superposed vertically spaced substantially parallel aprons for confining a layer of loose material therebetween, laterally spaced means for supporting said aprons and interposed material in a series of inert festoons depending from and hanging freely between said laterally spaced means, and means for supporting, maintaining and transporting said apron-supporting means in said laterally spaced relation.

15 2. The combination of a pair of superposed vertically spaced substantially parallel aprons for confining a layer of loose material therebetween, laterally spaced means for supporting said aprons and interposed material in a series 20 of inert festoons depending from and hanging freely between said laterally spaced means, and means for forming said aprons and interposed material simultaneously into a festoon at one end of said series.

25 3. The combination of a pair of superposed vertically spaced substantially parallel aprons for confining a layer of loose material therebetween, laterally spaced means for supporting said aprons and interposed material in a series 30 of inert festoons depending from and hanging freely between said laterally spaced means, means for forming said aprons and interposed material simultaneously into a festoon at one end of said series, and means for withdrawing 35 said aprons and interposed material simultaneously from a festoon at the opposite end of said series.

40 4. The combination of a pair of superposed vertically spaced substantially parallel aprons for confining a layer of loose material therebetween, laterally spaced means for supporting said aprons and interposed material in a series of inert festoons depending from and hanging freely between said laterally spaced means, means for 45 forming said aprons and interposed material simultaneously into a festoon at one end of said series, means for withdrawing said aprons and interposed material simultaneously from a festoon at the opposite end of said series, and means for 50 conveying said series of festoons bodily in said inert state from said forming to said withdrawing means.

55 5. The combination of a pair of superposed vertically spaced substantially parallel aprons for confining a layer of loose material therebetween, laterally spaced means for supporting said aprons and interposed material in a series of inert festoons depending from and hanging freely between said laterally spaced means, means for 60 forming said aprons and interposed material simultaneously into a festoon at one end of said series, means for applying said layer of material to one of said aprons prior to the formation of said aprons into said festoon, and means for applying the second apron to said layer of material intermediate the material-applying means and the apron-festooning means.

65 6. The combination of a pair of superposed vertically spaced substantially parallel aprons for confining a layer of loose material therebetween, laterally spaced means for supporting said aprons and interposed material in a series of inert festoons depending from and hanging freely between said laterally spaced means, means for 70 forming said aprons and interposed material si-

multaneously into a festoon at one end of said series, means for withdrawing said aprons and interposed material simultaneously from a festoon at the opposite end of said series, means for applying said layer of material to one of said aprons prior to the formation of said aprons into said festoon, means for applying the second apron to said layer of material intermediate the material-applying means and the apron-festooning means, and means for removing one of said aprons from said layer of material adjacent said withdrawing means to permit discharge of the material from the other of said aprons.

7. The combination of a pair of endless aprons, means for loading one of said aprons at a pre- 15 determined point in the endless course of travel thereof with a layer of loose material, means for applying a portion of the second apron to said layer of material in vertically spaced superposed and substantially parallel relation to the loaded 20 portion of the first said apron, laterally spaced means for supporting said portions of said aprons and said interposed layer of material in a series of inert festoons depending from and hanging 25 freely between said laterally spaced means, means for forming said apron portions and said interposed layer of material into a festoon at one end of said series, means for withdrawing said aprons and said layer of material from a festoon at the opposite end of said series, means for conveying 30 said series of festoons bodily in said inert state from said forming to said withdrawing means, means for separating the aprons from said interposed layer of material, and means for respectively guiding said separated aprons to said load- 35 ing and applying means respectively.

8. The combination in a conveyer of a pair of freely separable superposed vertically spaced substantially parallel aprons for confining a layer of loose material therebetween, laterally spaced 40 means for supporting said aprons and interposed material in a series of inert festoons depending from and hanging freely between said laterally spaced means, and means extending from each of said aprons into the interposed layer of material for preventing shifting of the material relative to the confining aprons in the depending portions of said festoons.

9. The combination in a conveyer of a pair of freely separable superposed vertically spaced substantially parallel aprons for confining a layer of loose material therebetween, laterally spaced means for supporting said aprons and interposed material in a series of inert festoons depending from and hanging freely between said laterally spaced means, and means extending from one of said aprons into the interposed layer of material for preventing shifting of the material relative to the confining aprons in the depending portions of said festoons.

10. The combination in a conveyer of an apron arranged to receive a superposed layer of loose material, laterally spaced means for supporting the apron and the superposed layer of material in a series of inert festoons depending from and hanging freely between said laterally spaced means, means for bodily transporting said inert festoons longitudinally of said laterally spaced supporting means, and means projecting from the apron into the layer of material thereon for 70 preventing shifting of the material relative to the apron in the depending portions of said festoons.

11. A drier for loose materials comprising a drying chamber, a conveyer comprising a pair of 75

freely separable superposed vertically spaced substantially parallel aprons confining a layer of said loose material therebetween for passage through said chamber, laterally spaced means in the upper portion of said chamber for supporting said aprons and interposed material therein in a series of inert festoons depending from and

hanging freely between said laterally spaced means and means in and movable longitudinally of said drying chamber for supporting, maintaining and transporting said apron-supporting means in said relation in and through said drying chamber. 5

ALPHEUS O. HURXTHAL.
